UNITED STATES PATENT OFFICE

98,959

DESIGN FOR A DENTAL UNIT

Oscar H. Pieper and Alphonse F. Pieper,
Rochester, N. Y.

Application July 5, 1935, Serial No. 57,532

Term of patent 14 years

To all whom it may concern:

Be it known that we, Oscar H. Pieper and Alphonse F. Pieper, citizens of the United States, residing at Rochester, in the county of Monroe and State of New York, have invented a new, original, and ornamental Design for a Dental Unit, of which the following is a specification, reference being had to the accompanying drawing forming a part thereof.

The figure is a front elevational view of a dental unit, showing our new design.

The back of the unit is substantially plain, is not deemed of importance from the standpoint of design and, therefore, is not shown.

The tumbler holder and shield is disposed between the cupidor and the column of the unit, as shown, and this is a dominant feature of the design of the unit.

We claim:—

The ornamental design for a dental unit, as shown and described.

In witness whereof, I hereunto subscribe my name this 1st day of July, 1935.

OSCAR H. PIEPER.

In witness whereof, I hereunto subscribe my name this 26th day of June, 1935.

ALPHONSE F. PIEPER.
